UNITED STATES PATENT OFFICE

170,361

INCINERATOR

Edward W. Lyons, Youngstown, Ohio

Application December 4, 1952, Serial No. 22,549

Term of patent 14 years

(Cl. D81—1)

To all whom it may concern:

Be it known that I, Edward W. Lyons, a citizen of the United States, residing at Youngstown, in the county of Mahoning and State of Ohio, have invented a new, original, and ornamental Design for an Incinerator, of which the following is a specification, reference being had to the accompanying drawing, forming a part thereof.

Figure 1 is a front perspective view of an incinerator, showing my new design.

Figure 2 is a back perspective view.

I claim:

The ornamental design for an incinerator, as shown.

EDWARD W. LYONS.
